CLAIM

The ornamental design for a fluid pump, as shown and described.

DESCRIPTION

FIG. 1 is a perspective view of a first embodiment of a fluid pump;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a third side view of the design of FIG. 1; and,

FIG. 7 is a fourth side view of the design of FIG. 1.

The broken lines shown in the drawings are included for the purpose of illustrating unclaimed portions of the fluid pump.

The broken lines form no part of the claimed design.
